[57] CLAIM

The ornamental design for a hand launcher for clay pigeons, substantially as shown and described.

DESCRIPTION

FIG. 1 is a perspective view of a launcher for clay pigeons showing my new design;

FIG. 2 is a bottom plan view thereof;

FIG. 3 is a side elevational view thereof;

FIG. 4 is a side elevational view of the side opposite that shown in FIG. 3;

FIG. 5 is an end elevational view thereof; and

FIG. 6 is an end elevational view of the end opposite that shown in FIG. 5.

Reference is made to co-pending U.S. Pat. No. 4,076,004, issued Feb. 28, 1978.
